UNITED STATES PATENT OFFICE.

WILLIAM CLARKE MARSHALL, OF CHICAGO, ILLINOIS.

TOBACCO-SMOKING PIPE.

No. 858,737.

Specification of Letters Patent.

Patented July 2, 1907.

Application filed August 16, 1906. Serial No. 330,867.

To all whom it may concern:

Be it known that I, WILLIAM CLARKE MARSHALL, a citizen of the United States, residing at Chicago, in the county of Cook and State of Illinois, have invented certain new and useful Improvements in Tobacco-Smoking Pipes; and I do declare the following to be a full, clear, and exact description of the invention, such as will enable others skilled in the art to which it appertains to make and use the same.

10 This invention relates to improvements in tobacco smoking pipes, and consists in the novel construction, combination and arrangement of parts hereinafter described and claimed.

15 The object of the invention is to provide a pipe of this character which may be quickly and easily cleaned and in which the temperature of the smoke may be readily controlled, so that the smoker may enjoy a cool smoke and secure the full pure benefit of the tobacco.

20 The above and other objects which will appear as the nature of my invention is better understood are accomplished by means of the construction illustrated in the accompanying drawings, in which:—

25 Figure 1 is a side elevation of the improved pipe; Fig. 2 is a top plan view of the same; Fig. 3 is a vertical longitudinal sectional view; Fig. 4 is a horizontal section. Fig. 5 is a detail, horizontal section through a slightly modified form of the invention.

30 In the practice of the invention, I provide the pipe with an outer bowl 1, an inner bowl 2 and air spaces or 35 channels 3 between these bowls. The outer bowl or body 1 of the pipe may be of any suitable form and construction and may have a stem 4 which may also be of any suitable form and construction. The inner bowl or cup 2 in which the tobacco is burned is formed of some durable material and has at its top an out-turned 40 annular flange 5, which rests upon the top of the outer bowl or body 1, as seen in Fig. 3. The air passages 3 are provided for the purpose of permitting a circulation of air between the two bowls of the pipe, so that the 45 temperature of the inner one will be reduced. These passages may be produced in any suitable manner. As shown in Fig. 3 they are produced by forming upon the inner wall of the outer bowl 1 vertically extending V-shaped ribs or corrugations 6, the points or edges of 50 which engage the outer face of the inner bowl 2, which latter is here shown in the form of a cylinder, but which may be of other shape. As shown in Fig. 5, the passages 3 are formed by making vertical grooves or channels in the inner wall of the body 1. In both cases, the 55 channels 3 extend vertically from the bottom 8 of the body 1 to its top and thus provide a plurality of flues for carrying off the heat generated by the burning tobacco in the bowl 2. The passage of air currents through the passages or channels 3 is made possible by providing in the center of the bottom 8 an opening 9 and by forming in the flange 5 of the bowl 2 an annular

row of apertures or openings 10, which latter align with the passages 3; also by forming in the body 1 adjacent to its top an annular row of transverse openings 11, which communicate with the upper ends of the passages 3, as clearly shown in Figs. 3 and 4. As indicated by the arrows in Fig. 3, currents of cool air will pass upwardly through the opening 9 and the passages 3 and then out through the openings 10, 11, carrying off the heat from the inner bowl 2.

60 While the construction above described materially reduces the temperature of the smoke, I prefer to further reduce it by admitting cool air into the bowl of the pipe adjacent to its bottom, especially after the tobacco in the bowl 2 has been partly consumed. I 65 preferably effect this by providing an inlet 12 at a suitable point adjacent to the bottom of the pipe. This opening 12 is here shown in the form of a tube extending across one of the channels or passages 3 and having its open ends secured in the inner and outer bowls. 70 It is adapted to be closed or opened by a removable closure of any description, as here shown it is in the form of a removable plug. The air inlet 12 is preferably arranged at a point diametrically opposite the opening 14 in the stem 4 of the pipe, so that a cleaning 75 wire or the like may be passed through the alining openings 12, 14 to facilitate cleaning the pipe.

80 In use, the tobacco is packed in the inner bowl 2 in the usual manner and the plug or closure 13 is placed in the opening 12. After the tobacco has been about 85 half consumed, the temperature of the smoke increases to a noticeable extent notwithstanding the cooling effects of the air currents passing through the air passages 3 as previously explained. When this occurs, the plug 13 may be removed from the opening 12 to 90 admit air into the bottom of the pipe. This air mingles with the smoke and cools it, so that the pleasure of the smoker is materially increased. The opening 12 aside from acting as a feeder of cool air to the over-heated smoke, serves as a damper to break or modify the supply of air through the open top of the bowl 2 and also as a perfect means of cleaning the pipe by inserting a 95 cleaning wire or the like as previously stated.

95 Various changes in the form, proportion and the minor details of construction may be resorted to without departing from the principle or sacrificing any of the advantages of this invention, as defined by the appended claims.

Having thus described my invention, what I claim as new and desire to secure by Letters-Patent, is:— 100

1. A tobacco pipe comprising an outer bowl having openings near the top thereof and a central air inlet in its bottom, an inner bowl spaced from the bottom and side walls of said outer bowl and having an annular flange at its top to engage the top of the outer bowl, said flange having apertures therein registering with the spaces between the bowls, and a stem connected with said bowls. 110
2. A tobacco pipe comprising an outer bowl having a

stem projecting therefrom and vertically extending ribs upon its inner wall, an inner bowl engaged with the edges of said ribs and having an annular flange at its top to engage the top of the outer bowl, said flange having apertures to aline with the spaces between said ribs, said outer bowl having in its bottom a central air inlet opening to afford communication between the atmosphere and the lower ends of the spaces between said ribs, said outer body also having adjacent to its top transverse openings to afford communication between the atmosphere and the upper ends of the spaces between said ribs, an air inlet

for the inner bowl arranged adjacent to its bottom and in alignment with the opening in the pipe stem, and a removable closure for said air inlet opening, substantially as shown and described:

In testimony whereof I have hereunto set my hand in presence of two subscribing witnesses.

WILLIAM CLARKE MARSHALL.
